UNITED STATES PATENT OFFICE.

HERBERT S. MILLS, OF CHICAGO, ILLINOIS.

VENDING-MACHINE.

SPECIFICATION forming part of Letters Patent No. 690,068, dated December 31, 1901.

Application filed January 14, 1901. Serial No. 43,136. (No model.)

To all whom it may concern:

Be it known that I, HERBERT S. MILLS, a citizen of the United States, residing at Chicago, in the county of Cook and State of Illinois, have invented new and useful Improvements in Vending-Machines, of which the following is a specification.

My invention relates particularly to a machine for vending small packages or blocks of material, such as packages of gum or the like.

My primary object is to provide a machine of generally-improved construction, particular attention being paid to simplicity of construction, cheapness of manufacture, and to capacity.

My invention is illustrated in its preferred form in the accompanying drawings, in which—

Figure 1 is a view in front elevation of a two-slot machine; Fig. 2, a plan view of a portion of the frame of the machine and showing also one of the rotary carriers employed; Fig. 3, a vertical section taken, as indicated, at line 3 of Fig. 1; Fig. 4, a broken vertical section taken similar to Fig. 3, but showing a different position of certain of the parts; Fig. 5, a section parallel to the front of the casing and looking toward the front of the machine; Figs. 6 and 7, rear views of a portion of the front of the casing and showing different positions of the coin-operated mechanism connected with the machine; and Figs. 8 and 9 similar views, but showing added parts.

Generally stated, the invention involves in its preferred form the use of a rotary carrier provided with vertically-disposed peripherally-arranged receptacles, coin-controlled mechanism through the medium of which said carrier is rotated, and means for locking the carrier against rotation when a receptacle becomes empty.

A represents the frame of the machine, comprising a base portion A', a superimposed portion A², superimposed commodity-receptacle chambers A³, a removable top A⁴ for said chambers, a lower casing-front portion A⁵, and an upper casing-front portion A⁶; B B', two coin-slots connected with the casing-front portion A⁵; C C', coin-controlled mechanisms corresponding with the two coin-slots; D, one of two horizontally-disposed shafts connected

with the coin-controlled mechanisms; D' D², bevel-gears connected with said horizontal shafts; E, coin-detectors, (one only being shown,) one member of which comprises a movable magnet E'; F, coin-actuated wheels comprising portions of the coin-controlled mechanisms; G, magnet-actuating devices connected with the coin-controlled mechanisms; H H', vertically-disposed carrier-actuating shafts provided with bevel-gears H² H³, engaging the gears D' D²; I I', rotary carriers supported from and rotated by the shafts H H'; I², vertically-disposed commodity-receptacles shown supplied with packages of gum or the like a; J J', Fig. 5, adjustable stops serving to engage the lowermost packages of gum as the receptacles rotate past the stops, delivering the same into a common discharge-chute J², and K combined carrier and coin-stops (one only being shown) pivoted at b.

The construction of the coin-controlled mechanism herein shown is fully disclosed in patent to me, No. 614,618, granted November 22, 1898, and my application, Serial No. 30,899, filed September 24, 1900. The construction of the coin-detector herein employed is now in common use, and no claim thereto will be made in the present application. The combined carrier and coin-stop herein shown is believed to be novel and will be fully described. The rotary carriers and the means directly connected therewith for operating them are believed to be novel.

As illustrated in Fig. 2, the portion A² of the frame has a flat rectangular top and is provided with perforations c, through which the vertical carrier-actuating shafts project. The rotary carriers comprise the base portions I I' and the vertically-disposed commodity-receptacles I², as clearly shown in Fig. 2. The commodity-receptacles are of rectangular cross-section and may be conveniently formed from sheet metal and fixed into sockets formed in the carrier-bases, as illustrated. In this construction the outer walls of the receptacles are formed by a stationary casing A⁸, which casing may be conveniently formed of two open-ended cylinders fitting into suitable sockets on the portion A² of the frame and surmounted by a common cap or cover A⁴, shaped to conform to said cylinders. The

outline of the cover A⁴ is indicated in dotted lines in Fig. 2, and the portion A² of the frame is shown provided at its top with perforations d for receiving bolts which extend from the top A⁴ and serve to secure the top and the cylinders A³ to the part A². As illustrated in Fig. 5, the lower margin of one lateral wall is cut away or recessed at f to permit a package to be discharged from the receptacle as the receptacle rotates over or past a stop J or J'. Each carrier-base has perforations g, through which packages may drop after being withdrawn from the receptacles, and each carrier-base also has circular slots g', which receive the studs J J' during the rotation of the carrier. The receptacles are arranged on the advance side of the perforations g, the studs J J' serving to engage the lowermost parcels as the carriers rotate and disengage said parcels from the bottoms whereon they are supported, causing them to fall through said perforations.

Each coin-controlled mechanism has as a portion thereof a manually-operated knob or handle h, connected with a rock-shaft h', carrying a coin-engaging arm h². The manner in which motion is communicated to the coin-wheel F through the medium of a coin interposed between the arm h² and studs on the wheel F is well understood in the art. As shown in Fig. 6, a passage k serves to conduct the coins from the bogus-coin detector to the coin-wheel.

Each carrier and the mechanism through which it is rotated is independent of the other carrier and its rotating mechanism, the machine being in reality a double machine with a common discharge-chute for the two carriers. The studs J and J' are so located that the packages from both carriers will be discharged at the chute J².

Each carrier-base is provided with a rim l, having recesses l', corresponding to the location of the receptacles I². The lower end of the stop K bears normally against the rim l under pressure from a spring m. As shown in Fig. 3, the packages of gum project out flush with the inner surface of the rim l, and the lower end of the stop K is provided with a beveled surface m'. As the lower end of the receptacle passes the lower end of the stop K said lower end of the stop enters the recess l' and bears upon the end of a package. Further rotation of the carrier causes the beveled surface to ride up onto the rim l. When there is no package in position to engage the lower end of the stop, the stop is free to move to the position shown in Fig. 4, thereby locking the carrier against further rotation. The inner wall of the coin-chute is provided with a perforation m², which permits the upper out-turned end of the stop K to move into the coin-passage when the lower end of the carrier-stop is in the locking position. (Shown in Fig. 4.)

The operation of the machine may be briefly stated. A coin is inserted at either of the

coin-slots B or B'. The customer may then turn the handle h which corresponds to the coin-slot in which the coin is deposited, and through the medium of the rock-shaft h', arms h², and inserted coin the coin-wheel F will be turned. The shaft D is rigid with the coin-wheel, and motion will therefore be communicated to the vertical carrier-actuating shaft 75 on the side of the machine which is being operated. As the carrier moves it carries one of its receptacles past the corresponding parcel-stop J or J' and the lowermost parcel or package is engaged by said stop and held against movement while the carrier continues its rotation. When freed from the receptacle, the parcel drops into the chute J² and is delivered to the purchaser. One actuation of the knob h serves to rotate a carrier through one-sixth 85 of a revolution in the construction shown, thereby delivering to the purchaser but one package. The lower end of the stop K rides upon the periphery of the carrier-base and over the ends of packages contained in the 90 receptacles until a receptacle is encountered which is empty, when the carrier is locked against further rotation and the upper portion of the stop enters the coin-slot, thereby preventing other coins from being fed into the 95 machine. The receptacles themselves thus have an orbital movement during actuation of the machine. The manner in which the magnet E' is actuated from the arm h² is described in my pending application, Serial No. 100,899, filed September 24, 1900.

Changes in details of construction within the spirit of my invention may be made. Hence no limitation is to be understood from the foregoing detailed description except as 105 shall appear from the appended claims.

What I claim as new, and desire to secure by Letters Patent, is—

1. In a vending-machine, a yieldingly-held movable carrier-stop, and a carrier having a 110 wall upon which one end of said stop rides and a recess which said stop may enter to lockingly engage the carrier when a receptacle needs recharging, substantially as described.

2. In a vending-machine, a rotary carrier 115 having vertically-disposed receptacles, a rim for the base of said carrier having recesses at said receptacles, and a yieldingly-held movable stop bearing normally upon said rim and riding across said recesses by contact with 120 packages until a receptacle becomes empty, when said stop serves to lock the carrier, substantially as described.

3. In a vending-machine, the combination of a rotary carrier having at its base a circumferential wall provided with recesses, vertically-disposed receptacles arranged at said recesses, and a pivoted stop K having one end engaging said circumferential wall, substantially as and for the purpose set forth. 125 130

4. In a vending-machine, a rotary carrier having peripherally-arranged vertical receptacles and having its bottom recessed to receive a package-stop, and having also a cir-

5 circumferential wall at its base recessed to receive a carrier-stop, a package-stop beneath said carrier and having its upper end projecting above the base-walls of said receptacles, and a yieldingly-held movable carrier-stop having an end bearing normally upon said circumferential wall and the ends of the

6 packages in said receptacles, substantially as and for the purpose set forth.

HERBERT S. MILLS.

In presence of—

D. W. LEE,

ALBERT D. BACCI.
